UNITED STATES PATENT OFFICE.

FRANK R. NORTHAM, OF CHICAGO, ILLINOIS, ASSIGNOR TO THE ANGLO-AMERICAN PROVISION COMPANY, OF SAME PLACE.

CAR-TRUCK BEARING.

SPECIFICATION forming part of Letters Patent No. 653,522, dated July 10, 1900.

Application filed February 12, 1900. Serial No. 4,943. (No model.)

To all whom it may concern:

Be it known that I, FRANK R. NORTHAM, a citizen of the United States of America, and a resident of Chicago, in the county of Cook 5 and State of Illinois, have invented certain new and useful Improvements in Car-Truck Bearings, of which the following is a specification.

My invention relates particularly to center 10 bearings and side bearings for railway-trucks. Its main object is to provide improved means for raising the car-body from the truck to allow for sagging of said body. I accomplish this object by the mechanism shown in the 15 accompanying drawings, in which—

Figure 1 is a front elevation, partly sectional, showing the upper part of a truck and the lower part of a car-body, having my improved form of bearings applied thereto. 20 Fig. 2 is a top plan of the part of the side bearings secured to the truck. Fig. 3 is a vertical section of same on the line 33 of Fig. 2. Fig. 4 is a top plan of the center plate secured to the car-body. Fig. 5 is a bottom 25 plan of same. Fig. 6 is an enlarged central vertical section of the center bearing, taken on the line 66 of Fig. 1. Fig. 7 is a top plan of the removable plate shown between the upper and lower plates in Fig. 6. Fig. 8 is a 30 central vertical section of same on the line 88 of Fig. 7. Fig. 9 is a top plan of the center plate secured to the truck, showing same slightly reduced from the size shown in Fig. 6. Fig. 10 is a vertical central section of 35 same on the line 1010 of Fig. 9.

The center plate 1 is secured upon the truck 2 by means of the bolts 4. The center plate 5 is secured to the car-body 7 by means of the bolts 9. The plate 11 is inserted between 40 the plates 1 and 5 when it is desired to raise the car-body on the truck. The side bearings each consist of the supporting member or socket-piece 12, which is secured to the truck by bolts 13, a block 14, secured to the car-body by bolts 15, a block 16, fitting in said socket, and a block 17, which is inserted in the socket-piece under the block 16 when it is desired to raise the car-body to the position shown in Fig. 1. The plate 5 has the depending convex projection 18, which is made to

fit into the socket 19 of the plate 1 and the socket 20 of the plate 11. The convex part 18 has a central recess 21 for receiving the tubular projection 22 on the plate 1. The plates 1 and 5 have the central apertures 23 55 and 24, through which the car body and truck are pivotally connected in the usual manner.

The plate 11 has a central aperture 25 for receiving the tubular projection 22 of the plate 1. The plate 1 has its concaved face 60 19 on the raised part, which is flattened on opposite sides, as at 26. The flanges 27 of the plate 11 abut against said flattened parts 26, and thus prevent the plate 11 from rotating on its seat. 65

In Fig. 4 the reference-numeral 27 represents depressions in the upper face of said plate, which serve merely to decrease the weight. 28 represents tubular reinforcements around the bolt-holes 29. Other bolt-holes 30 are provided in different plates for securing same in proper position. 31 represents reinforcing-rims for the bolt-holes 30 in the plates 1 and 5. 70

The operation of my device is as follows: 75 It will be understood that after a car has been used for some time the car-body will sag downwardly. It has therefore been found necessary to raise the car-body slightly on its bearings. This has been done heretofore by 80 removing the lower center plate and securing a block under same. The side bearings, which have consisted of plates of metal blocks, have been raised in a similar manner by removing same from the truck and securing an additional block under same. In my device the car will first be used without the plate 11 and block 17. It will be seen that the face 18 of the plate 5 will then rest upon the concave face 19 of the plate 1 and the block 16 will 85 rest upon the bottom of the socket in the member 12. After the car-body has sagged so that it is desirable to elevate same at the bearings the operator will merely cause the body to be raised from the truck and insert 90 the plate 11. He will also remove the block 16 and insert the block 17 under same. 95

It will be understood that some of the details of construction in the device shown may be altered without departing from the spirit 100

of my invention. I therefore do not confine myself to such details except as hereinafter limited in the claims.

What I claim as my invention, and desire 5 to secure by Letters Patent, is—

1. The combination of a car-truck and car-body, with a center bearing-plate secured to each, one of said plates having a convex face and the other having an oppositely-formed 10 depression for receiving the convex part, a removable concavo-convex plate fitting between said other plates, a socket-piece secured to the truck at each side of its center plate, and a pair of separable blocks seated in said 15 socket-piece one above the other, the upper block being vertically movable in said socket-piece and supported in a raised position by said lower block, substantially as and for the purpose specified.
2. The combination of a car-truck and car-body, with a center bearing-plate secured to each, one of said plates having a convex face and the other having an oppositely-formed 20 depression for receiving the convex part, a removable concavo-convex plate fitting between said other plates, and a pair of side 25 bearings located on opposite sides of said center plates; each of said side bearings comprising a supporting member, a vertically-

movable bearing-piece slidingly engaging 30 said supporting member and means for fixing the relative vertical position of said bearing-piece and supporting member, substantially as and for the purpose specified.

3. The combination of a car-truck and car-body, with a center bearing-plate secured to each, one of said plates having a convex face and the other having an oppositely-formed 35 depression for receiving the convex part, a removable concavo-convex plate fitting between said other plates, and being engaged by one of said bearing-plates against relative 40 rotation, and a pair of side bearings located on opposite sides of said center plates; each of said side bearings comprising a supporting 45 member, a vertically-movable bearing-piece slidingly engaging said supporting member, and means for fixing the relative vertical position of said bearing-piece and supporting member, substantially as and for the purpose 50 specified.

Signed by me at Chicago, Illinois, this 8th day of February, 1900.

FRANK R. NORTHAM.
